(57) **CLAIM**

The ornamental design for an electronic device display screen with transitional graphical user interface, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of the first image of the display screen with transitional graphical user interface;

FIG. 2 is a front view of the second image thereof;

FIG. 3 is a front view of the third image thereof;

FIG. 4 is a front view of the fourth image thereof;

FIG. 5 is a front view of the fifth image thereof;

FIG. 6 is a front view of the first image of a second embodiment thereof;

FIG. 7 is a front view of the second image thereof;

FIG. 8 is a front view of the third image thereof;

FIG. 9 is a front view of the fourth image thereof; and,

FIG. 10 is a front view of the fifth image thereof.

The appearance of the image transitions sequentially between the images shown in FIGS. 1-5 and 6-10, respectively. The process or period in which an image transitions to another image forms no part of the claimed design.

The longer broken line showing an electronic device forms no part of the claimed design.

The shorter broken line showing a display screen forms no part of the claimed design.
